ERNEST R. GODWARD, OF NEW YORK, N. Y.

VAPORIZER

Application filed December 7, 1928. Serial No. 324,553.

This invention relates, generally, to improvements in means for vaporizing volatile liquid fuel mixtures; and the invention has for its principal object to provide a novel form and construction of apparatus for treating mechanical mixtures of liquid fuels (such as hydrocarbons or other volatile combustible liquids) and air, whereby the mixture is initially passed through a relatively highly heated zone having supporting surfaces to receive heavier or less volatile constituents of the fuel mixture to delay the progress thereof so as to subject the same to vaporizing effect of maximum heat, whereupon the mixture is discharged from said initial hot zone into and through a succeeding vaporizing chamber or chambers wherein additional supporting surfaces furnished by plate elements, for any remaining wet fuel particles is provided; said latter plate elements being conductive of heat transmitted thereto from an underlying secondary hot plate, whereby wet fuel particles deposited thereon are subject to a treatment by heat in nature of fractional distillation while continuing in the presence of and subject to the frictional evaporative effects of the moving fuel mixture streams from which they have been separated, and yet held ready for return to or absorption by said mixture streams immediately the volatilization point thereof is attained.

Other objects of this invention, not at this time more particularly enumerated, will be readily understood from the following detailed description of the same.

The invention is illustrated in the accompanying drawings, in which:—

Fig. 1 is a vertical longitudinal section through a vaporizer device showing one embodiment of the principles of the present invention; Fig. 2 is a top plan view of the same with the cover section thereof removed and looking down into a secondary vaporizing chamber thereof; and Fig. 3 is a horizontal section through the primary vaporizing chamber thereof, taken on line 3—3 in Fig. 1.

Fig. 4 is a fragmentary vertical longitudinal section through a modified form of vaporizer device, still embodying, however, the principles of this invention; and Figure 5 is a

sectional view of the same, with the cover section thereof removed, and taken on line 5—5 in Fig. 4.

Similar characters of reference are employed in all of the hereinabove described views, to indicate corresponding parts.

Referring first to Figs. 1 to 3 inclusive, the vaporizing device as therein illustrated comprises, a casing or housing 1 having an open upper end normally closed by a cover member 2, which is suitably secured to the upper open end of the casing or housing 1. The interior of the casing or housing 1 is sub-divided by an inverted conical bottom plate 3, to provide a heater chamber 4 at the lower end of the housing or casing 1. The housing or casing 1 is provided with a fuel mixture intake 5, which leads centrally into the lower end of the housing or casing interior, the same being formed by a centrally located throat member 6 which rises through the interior of the heater chamber 4 to extend intermediate the outer bottom wall of said housing or casing to and through the bottom plate 3.

The housing or casing is provided at opposite sides with laterally extending necks 7 and 8, respectively providing inlet and outlet passages 9 and 10 leading into and out of the heater chamber 4, and through which, in connection with suitable delivering and discharging conduits (not shown) a heating medium (such e. g. as the exhaust gases from an internal combustion engine) may be introduced into and circulated through the heater chamber 4, so as to transfer heat to the bottom plate 3.

The inverted conical bottom plate 3 slopes downwardly and inwardly toward and converging upon said fuel mixture intake 5, preferably at an angle approximating 45 degrees.

Arranged within the interior of the housing or casing 1, above the bottom plate 3, is a fitting comprising a partition member 11, which is preferably also of inverted conical form but of shallower angularity than is the bottom plate 3. This partition member 11 is of smaller diameter than the inner diameter of the casing or housing 1, so as to provide a concentric annular opening or passage 12 intermediate its periphery and the sides of said

housing or casing. This partition member 11 is spaced above the bottom plate 3 so as to provide an intermediate zone of maximum heat contiguous to said bottom plate 3, adapted to provide a primary vaporizing chamber into which the fuel mixture intake 5 leads, and which has its outlet by way of the annular opening or passage 12.

Extending between the partition member 10 11 and bottom plate 3, and radially from the fuel mixture intake 5 to the annular opening or passage 12, are a plurality of curved or arcuate plates 13, so spaced as to provide a plurality of curved intermediate passages 15 contiguous to which is a very considerable area of supporting surface which the sides of said plates 13 provide. The primary vaporizing chamber thus provided is immediately above the bottom plate 3 to which the maximum degree of heat is transferred from the heating chamber 4, so that said primary vaporizing chamber, including the curved plates 13 are at a maximum heat during operation of the device, and much of the heat transferred thereto by radiation from the bottom plate 3 and by conduction through the curved plates 13 also serving to heat the partition member 11.

The interior of the housing or casing 1 above the partition member 11 (as shown in Figs. 1 and 2) provides a secondary vaporizing chamber. Extending upwardly from said partition member 11, and radially from a center hub or column 14 to the annular opening or passage 12, are a plurality of curved arcuate plates 15, so spaced as to provide a plurality of curved intermediate passages contiguous to which is a very considerable area of supporting surface provided by the sides of said plates 15. Said plates 15 are reversely curved as compared with the curvature of the plates 13, for the reason that the intake ends of the passages intermediate the plates 15 communicates with annular opening or passage 12, the outlet of said passages being at the upper ends thereof so as to discharge into the cover member 2. Said cover member 2 is provided with a discharge passage 16, which, in practice, is connected 50 with the fuel delivery manifold of an internal combustion engine or other device to be served by the vaporizer.

In operation, a mechanical mixture of volatile liquid fuel and air (such as is delivered by any well known carburetting device) is delivered to the vaporizing apparatus through the fuel mixture intake 5, as, for example, under the suction of the fuel intake strokes of the pistons of an internal combustion engine served by said vaporizing apparatus. The fuel mixture, thus entering the vaporizer apparatus, is deflected by the partition member 11, and is caused to enter and traverse the passages of the primary vaporizing chamber intermediate the plates 13, the

same moving toward the annular opening or passage 12. As will be obvious, the primary vaporizing chamber is contiguous to the bottom plate 3, which is maintained at maximum temperature by the heating medium circulated through the heating chamber 4, and consequently said primary vaporizing chamber constitutes a zone of maximum heat, not only receiving heat radiated from the hot bottom plate 3, but also having its curved plates 13 highly heated by conduction from said bottom plate 3, with which the lower ends of said curved plates 13 are in contact. Owing to the curvature of said plates 13, and the corresponding curvature of the passages 80 intermediate the same, the fuel mixture traversing said passages is given a centrifugal movement, whereby unvaporized particles of liquid contained in the mixture are caused to impinge upon the surfaces of said curved plates 13, so as to be caught thereon and supported subject to the effect of the heat within the hot zone and that conducted through said curved plates, whereby vaporization of the liquid fuel particles, and particularly the heavy ends thereof, is hastened by heat. Any wet fuel particles not immediately vaporized by contact with the surfaces of the hot curved plates 13, will tend to trickle down such surfaces toward the hotter lower portions of said curved plates 13 and in the end upon the hot bottom plate 3, being readily vaporized as a degree of heat adequate to such effect is met with. In addition to the vaporizing effect of the heat, thus applied to the wet fuel particles, and particularly to the heavier ends of the volatile fuel, the thus supported wet fuel particles are also subjected to the frictional vaporizing effect of the moving stream of fuel mixture. The 105 passages of the primary vaporizing chamber are of increasing area from intake toward discharge ends thereof, so that the movement of the stream is slowed down and expansion thereof permitted, which in combination with the centrifugal motion imparted tends to quickly deposit the heavier wet fuel particles on the supporting surfaces of the curved plates 13 subject to the heat induced vaporizing effects above described.

The fuel mixture is discharged from the primary vaporizing chamber through the annular passage 12 in the form of a fog or mist, from which substantially all the heavier wet particles have been separated by the vaporizing effects occurring in the primary vaporizing chamber. The fuel mixture is thereupon caused to enter the secondary vaporizing chamber above the partition member 11, and to spread through the curvilinear passages thereof bounded by the reversely curved plates 15, the same tending to flow obliquely upward therethrough for final discharge from the top ends of said passages into and through the cover section 2. Owing to the 13

curvilinear shape of these passages, the fuel mixture continues to be subjected to a centrifugal motion tending to throw any remaining wet particles contained therein upon the supporting surfaces provided by the surfaces of the curved plates 15 contiguous to said passages, whereby the progress of the same is delayed sufficiently to permit of evaporation thereof. Since the partition member 11 is more or less heated owing to its contiguity to the hot zone formed by the primary vaporizing chamber, and owing to the fact that the heat thereof tends to be conducted upwardly through the curved plates 15, the wet fuel particles deposited on the surfaces of the latter are again subjected to increasing heat as they trickle down, under gravity, the said surfaces, and consequently these particles are subjected to both the vaporizing effects of heat and friction of the moving mixture streams, so as to be finally vaporized and returned to said outgoing fuel mixture stream.

Owing to the reverse curvature of the plates 15 of the secondary vaporizing chamber, there is no abrupt change of direction of movement of the fuel mixture streams as the same flow from the primary to and through the secondary vaporizing chamber, but rather passages of somewhat ascending spiral conformation are formed through the vaporizing chambers, whereby a smooth unimpeded and unrestricted flow of the fuel mixture is assured, with the development of sufficient centrifugal effect at all points of its travel to assure both deposit of wet fuel particles upon the plate surfaces and frictional contact of the fuel streams with said surfaces.

From the above description it will be apparent, that the raw carburetted fuel mixture is first subjected to a maximum heat effect while traversing the primary vaporizing chamber and then to a reduced or milder heat effect while traversing the secondary vaporizing chamber, whereby the heavy ends of the liquid fuel are all initially treated and substantially vaporized in the initial hot zone of the primary vaporizing chamber, while any remaining liquid particles are delayed and vaporized in the secondary vaporizing chamber. As a result the resultant vaporized fuel mixture has an opportunity to cool down somewhat before it is finally discharged to the place of use, e. g. internal combustion engine cylinders.

While I have shown in Figs. 1 to 3 inclusive a simple form of vaporizer apparatus embodying the principles of this invention, and comprising a primary hot zone vaporizing chamber and a single secondary vaporizing chamber, it will be understood that I may increase the number of secondary vaporizing chambers, if desired. For example, I have shown in Figs. 4 and 5 a modified arrangement and construction of vaporizer device, in which the fuel mixture streams are

led from a primary hot zone vaporizing chamber to a succeeding secondary vaporizing chamber, and from the latter on through a third vaporizing chamber. In said Figs. 4 and 5 the construction of the housing or casing and the primary vaporizing chamber is the same as already described in connection with the structure shown in Figs. 1 to 3 inclusive, the parts thereof being identified by corresponding characters of reference. Spaced above the partition member 11 (which is disposed to provide the annular outgoing passage 12 from the primary vaporizing chamber) is another partition member 17, preferably of shallower conical angle than that of the partition member 11; said partition member 17 having a central discharge opening 18. Arranged within the space intermediate the partition member 11 and the partition member 17, and so as to extend upwardly from the former to the latter, and radially inward from the sides of the casing or housing 1 to a central passage 19, are a plurality of curved or arcuate plates 20 and shorter intermediate plates 21, so spaced as to provide a plurality of curved inwardly reaching passages contiguous to which is a very considerable area of supporting surface provided by the sides of said plates 20 and 21. Said passages extend from the annular opening 12 to the central passage 19 upon which they converge, and the plates 20-21 and intermediate passages are preferably reversely curved as compared with the curvature of the plates 13 and passages intermediate the latter, which lie within the primary vaporizing chamber.

Spaced above the partition member 17 is a top partition member or plate 22, which is of smaller diameter than the inside diameter of the casing or housing 1 so as to provide an annular discharge opening or passage 23 leading into the cover section 2. Arranged within the space intermediate the partition member 17 and partition member or plate 22, and so as to extend upwardly from the former to the latter, and radially outward from the central passage 19 to the sides of said casing or housing 1, are a plurality of curved or arcuate plates 24, and shorter intermediate plates 25, so spaced as to provide a plurality of curved outwardly reaching passages contiguous to which is a very considerable area of supporting surface provided by the sides of said plates 24-25. Said plates 24-25, and the passages defined thereby, are preferably reversely curved as compared with the curvature of the plates 20-21 and passages formed thereby. It will thus be obvious that the fuel mixture in traversing the several chambers from intake to discharge points of the vaporizer will proceed with a continuous smooth sweeping movement from one chamber to the other. It will also be noticed that the heights of the chambers in which the streams move outwardly

are decreased to compensate for the increasing width of the passages toward their discharge ends, while the heights of the chamber in which the streams move inwardly is increased to compensate for the decreasing width of the passages toward their discharge ends. In practice, the cross-sectional dimensions of the passages in all cases is desired to gradually increase from intake to discharge points, so that expansion of the moving fuel streams is progressive with consequent desired slowing up of the speed of movement thereof.

In the modified arrangement of vaporizer as immediately above described, the maximum zone of heat is provided in the lowermost or primary vaporizing chamber, and owing to the spacing of the succeeding vaporizing chambers in progressively removed relation to the source of heat, the temperature effects are reduced toward the discharge end of the vaporizer as a whole, thus allowing for the cooling down of the vaporized fuel mixture, while yet retaining all the advantages of supporting plate surface with consequent provision of time and that degree of heat best calculated to treat unvaporized liquid fuel particles at all stages of the progress of the fuel mixture stream through the vaporizer.

Attention may here be called to the fact that the structure provided by the instant form of vaporizer permits the production of plate sections by casting or molding processes, if desired; the plates being cast integral with the partition plate 11 in a type of construction such as illustrated in Figs. 1 to 3 inclusive, or in groups respectively integral with the partition plates 11, 17 and 22 as in the type of construction such as illustrated in Figs. 4 and 5. Another advantage of the construction comprising a casting or castings, lies in the fact that the plates have substantial thickness, and consequently the same are more efficiently heat conductive.

While in Figs. 1 to 3 inclusive I have omitted the showing of shorter plates intermediate the full length plates in the manner shown in Figs. 4 and 5, it will nevertheless be understood that such shorter plates may also be provided in the former construction should it be so desired.

I am aware that various changes may be made in the arrangements and combinations of the several devices and parts, as well as in the details of the construction of the same, without departing from the scope of this invention as set forth in the foregoing specification and as defined in the appended claims. Hence, I do not limit my invention to the exact arrangements and combinations of the several devices and parts as described in the foregoing specification; nor do I confine myself to the exact construction of said

parts as illustrated in the accompanying drawings.

I claim:

1. A vaporizing device, comprising a housing having a central carburetted fuel mixture inlet, a bottom plate, means to heat said bottom plate, a partition member spaced above said bottom plate to provide an initial vaporizing chamber contiguous to said bottom plate and into which said inlet leads, said chamber being subjected to the maximum heat effects of said bottom plate, said partition member being of less diameter than the inside diameter of said housing to provide an annular opening leading out of said chamber, additional vaporizing space above said partition member, and means in said chamber and in said space to impart centrifugal movement to fuel mixture streams passing therethrough and to provide both supporting surface for unvaporized liquid fuel particles and means to conduct heat to the latter when deposited on said surface.

2. A vaporizing device, comprising a housing having a central carburetted fuel mixture inlet, a bottom plate, means to heat said bottom plate, a partition member spaced above said bottom plate to provide an initial vaporizing chamber contiguous to said bottom plate and into which said inlet leads, said chamber being subjected to the maximum heat effects of said bottom plate, said partition member being of less diameter than the inside diameter of said housing to provide an annular opening leading out of said chamber, additional vaporizing space above said partition member, a plurality of curved radial plates extending outwardly through said chamber and disposed between said hot bottom plate and said partition member and to the lower ends of which heat is transferred from said bottom plate for upward conduction therethrough, and a plurality of reversely curved radial plates projecting upwardly from said partition plate and to the lower ends of which heat is transferred from said partition plate for upward conduction therethrough, said latter plates providing outgoing passages communicating with said annular opening leading out of said initial vaporizing chamber.

3. A vaporizing device, comprising a casting having a central carburetted fuel mixture inlet leading into the bottom and a vaporized fuel mixture outlet leading from the upper portion thereof, a bottom plate downwardly inclined to converge on said inlet, means to heat said bottom plate, a partition member spaced above said bottom plate to provide an initial vaporizing chamber contiguous to said bottom plate and subject to the maximum heating effects of the latter, said partition member being arranged to provide an annular discharge opening for said chamber, and a vaporizing means com-

- prising a plurality of spaced radially disposed vertical plates rising upwardly from said partition member to provide a plurality of radial passages extending between said 5 annular discharge opening and said vaporized fuel mixture outlet of said casing, heat from said partition being conducted to the lower ends of and upwardly through said plates.
- 10 4. A vaporizing device, comprising a casing having a central carburetted fuel mixture inlet leading into the bottom and a vaporized fuel mixture outlet leading from the upper portion thereof, a bottom plate downwardly inclined to converge on said inlet, means to heat said bottom plate, a partition member spaced above said bottom plate to provide an initial vaporizing chamber contiguous to said bottom plate and subject to the maximum 15 heating effects of the latter, said partition member being arranged to provide an annular discharge opening for said chamber, and a vaporizing means comprising a plurality of spaced radially disposed vertical 20 plates rising upwardly from said partition member to provide a plurality of radial passages extending between said annular discharge opening and said vaporized fuel mixture outlet of said casing, heat from said partition plate being conducted to the lower ends of and upwardly through said plates, said plates being curved to impart centrifugal movement to streams of fuel mixture traversing the passages bounded thereby.
- 25 5. A vaporizing device, comprising a casing having a central carburetted fuel mixture inlet leading into the bottom and a vaporized fuel mixture outlet leading from the upper portion thereof, a bottom plate downwardly inclined to converge on said inlet, means to heat said bottom plate, a partition member spaced above said bottom plate to provide an initial vaporizing chamber contiguous to said bottom plate and subject to the maximum 30 heating effects of the latter, said partition member being arranged to provide an annular discharge opening for said chamber, a plurality of curved radial plates standing between said bottom plate and said partition member to provide intermediate passages extending between said fuel mixture inlet and said annular discharge opening, said plates being adapted to conduct heat upwardly from said bottom plate to said partition member, and being further adapted to provide a substantial area of heated supporting surface for deposit of unvaporized liquid fuel particles separated from the fuel mixture streams by centrifugal movement of the latter through said passages, a plurality of reverse- 35 curved radial plates upstanding from said partition member to provide intermediate passages between said annular discharge opening and the vaporized fuel mixture outlet of the casing, said latter plates being
- adapted to conduct heat upwardly from said partition member, and being further adapted to provide a substantial area of progressively heated supporting surface for deposit of unvaporized liquid fuel particles separated from the fuel mixture streams by centrifugal movement of the latter through the intermediate passages.
6. A vaporizing device comprising a casing having its interior divided into a plurality of successive vaporizing chambers including a lower chamber and an upper chamber, each vaporizing chamber having spaced and curved radial plates to impart centrifugal movement to the fuel mixture streams moving therethrough, means of communication between said chambers, means connected with said casing for admitting a carburetted fuel mixture to the lower chamber, means connected with said casing for discharging the vaporized fuel mixture from the upper chamber, and means for applying heat to the bottom of said lower chamber whereby the latter provides an initial zone of maximum heat and the upper chamber a zone of minimum heat.
- In testimony that I claim the invention set forth above I have hereunto set my hand this 5th day of December, 1928.
